[57] CLAIM

The ornamental design for lock assembly for zippered luggage, as shown and described.

DESCRIPTION

FIG. 1 is a front elevational view of a lock assembly for zippered luggage showing my new design, with the assembly shown disengaged;

FIG. 2 is a top plan view thereof, in an assembled position;

FIG. 3 is a bottom plan view thereof, in an assembled position;

FIG. 4 is a right end elevational view thereof, in an assembled position;

FIG. 5 is a top, front perspective view thereof, in an assembled position;

FIG. 6 is a rear elevational view thereof, in an assembled position; and

FIG. 7 is a left side elevational view thereof, in an assembled position.
